UNITED STATES PATENT OFFICE.

WILLIS H. SARGENT, OF ST. JOHNSBURY, VERMONT, ASSIGNOR TO THE
E. & T. FAIRBANKS & CO., OF ST. JOHNSBURY, VERMONT, A CORPO-
RATION OF VERMONT.

DESIGN FOR A SCALE-BASE AND SUPPORTING-COLUMN.

SPECIFICATION forming part of Design No. 35,970, dated July 1, 1902.

Application filed May 12, 1902. Serial No. 107,046. Term of patent 7 years.

To all whom it may concern:

Be it known that I, WILLIS H. SARGENT, a citizen of the United States, residing at St. Johnsbury, in the county of Caledonia, State of Vermont, have invented a certain new and original and ornamental Design for a Scale-Base and Supporting-Column, of which the following is a description, reference being had to the accompanying drawing, and to the letters of reference marked thereon.

My invention relates to a new and original design for a scale-base and supporting-column; and the leading feature thereof consists of the peculiar shape and configuration of the column, which extends between the base and the parts which support the operative portions of the scale.

In the drawing, the figure represents a perspective view of a scale-base embodying my design.

In the drawing, A represents the base proper,

and B B the parts supporting the scale-beam. The parts B B are formed upon the upper ends of the wings of an eagle, said wings being outstretched and in a backward position. 25 The eagle is supported upon a round base C of a column and carries in his beak a serpent, which is twined around so that the lower part of the body of the serpent is held in the talons of the bird, and below the bird is represented 30 a cactus-plant.

Having thus described my invention, what I claim as new, and desire to secure by Letters Patent, is—

The ornamental design for a scale-base; substantially as shown and described. 35

In testimony whereof I affix my signature in presence of two witnesses.

WILLIS H. SARGENT.
